US0D1037521S

(12) **United States Design Patent** (10) **Patent No.:** **US D1,037,521 S**
(45) **Date of Patent:** ** *Jul. 30, 2024

(54) **STAND LIGHT**

(71) Applicant: **Milwaukee Electric Tool Corporation**,
Brookfield, WI (US)

(72) Inventors: **Kyle Harvey**, Wauwatosa, WI (US);
Ross McIntyre, Milwaukee, WI (US);
Eric Mackey, Milwaukee, WI (US);
Justin Dorman, Wauwatosa, WI (US)

(73) Assignee: **MILWAUKEE ELECTRIC TOOL
CORPORATION**, Brookfield, WI (US)

(*) Notice: This patent is subject to a terminal disclaimer.

(**) Term: **15 Years**

(21) Appl. No.: **29/751,339**

(22) Filed: **Sep. 21, 2020**

Related U.S. Application Data

(63) Continuation of application No. 29/731,144, filed on Apr. 13, 2020, now Pat. No. Des. 902,463, which is a continuation of application No. 29/689,503, filed on Apr. 30, 2019, now Pat. No. Des. 883,549, which is a continuation of application No. 29/637,537, filed on Feb. 20, 2018, now Pat. No. Des. 850,689, which is a continuation of application No. 14/877,675, filed on Oct. 7, 2015, now Pat. No. 10,378,739.
